Des. 238,306
Patented Dec. 30, 1975

238,306

PORTABLE TRANSACTION LOG RECORDER

Elliot W. J. Spurway, Jr., Concord, Calif., assignor to Dymo Industries, Inc., San Francisco, Calif.

Filed Jan. 23, 1974, Ser. No. 435,997

Term of patent 14 years

Int. Cl. D18—02

U.S. Cl. D64—11 B

FIG. 1

FIG. 2

FIG _ 3

FIG _ 4

FIG _ 5

FIG _ 6

FIG _ 7

FIG. 1 is a perspective view of a portable transaction log recorder showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and

FIG. 7 is a bottom plan view thereof.

I claim:

The ornamental design for a portable transaction log recorder, substantially as shown.
